United States Patent Office

Des. 182,239
Patented Mar. 4, 1958

182,239

PENCIL

Grace L. Hartline Lemon, Tampa, Fla.

Application March 12, 1957, Serial No. 45,223

Term of patent 3½ years

(Cl. D74—17)

FIG.2

Fig. 1 is a perspective view of a pencil showing my new design; and

Fig. 2 is a cross-sectional view thereof, taken along the lines 2—2 of Fig. 1, looking in the direction of the arrows.

I claim:

The ornamental design for a pencil, substantially as shown.
